UNITED STATES PATENT OFFICE.

CHARLES A. FRENCH, OF CHICAGO, ILLINOIS, ASSIGNOR TO INTERNATIONAL HARVESTER COMPANY, OF CHICAGO, ILLINOIS, A CORPORATION OF NEW JERSEY.

VAPORIZING FUEL BURNER.

Application filed June 8, 1922. Serial No. 566,713.

To all whom it may concern:

Be it known that I, CHARLES A. FRENCH, a citizen of the United States, residing at Chicago, in the county of Cook and State of

Illinois, have invented certain new and useful Improvements in Vaporizing Fuel Burners, of which the following is a full, clear, and exact specification.

My invention relates to fuel burners and particularly to vaporizing burners especially adapted for use with automotive steam boilers.

Heretofore burners utilizing liquid fuel have vaporized the fuel by heating it in a coil or other form of retort which causes cracking and deposits heavy, sticky hydrocarbons in the passages; or the fuel has been atomized by an air spray or atomizing nozzle which produces a fine mechanical division of the fuel but, on burning, deposits carbon in the burner passages and combustion chamber. With either of these systems or methods frequent shut-downs for cleaning the burner are necessary.

It is an object of my invention to provide a burner in which the fuel is vaporized in the presence of air, the vaporization being complete before the vapor reaches the combustion zone so that there will be no deposits in either the vaporizing chamber or combustion space and, consequently, a clean, hot, short, blue flame indicative of perfect combustion will be obtained.

Another object is to provide a heated chamber for the vaporization of the fuel in a combustible mixture and to separate the vaporized and heated mixture from the unvaporized portion, delivering only thoroughly vaporized fuel to the combustion zone.

I attain the above and many other important objects by the embodiment of my invention shown in the accompanying drawings in which—

Fig. 1 is a longitudinal section of my improved vaporizing burner taken on the line 1—1 of Fig. 2;

Fig. 2 is a section on the line 2—2 of Fig. 1;

Fig. 3 is a plan, partly in section, of the pilot burner taken substantially on the line 3—3 of Fig. 1;

Fig. 4 is a plan of the top section of the lower part of the burner grating;

Figs. 5 and 6 are details of burner sections;

Fig. 7 is a section of the lighting tube for carrying flame from the lower to the upper burner sections, the section of the figure being taken on the line 7—7 of Fig. 1;

Fig. 8 shows the bottom protector plate; and

Fig. 9 is an enlarged view of the air and fuel inlet pipes for the pilot burner.

The form of my invention disclosed in the drawings for purposes of illustration comprises a vaporizing drum 10, upper and lower burner sections 11, 12 and a pilot or secondary burner 13. In the normal operation of the burner, the lower section 12 heats the vaporizing drum 10 but, when the main burner is shut off, the pilot burner 13 keeps the drum hot until the main burner is again turned on.

The vaporizing drum has a hollow circular body to which a mixture of fuel and air is supplied through a tangential inlet 14 and has upper and lower central discharge openings 15, 16 in communication with the burner sections 11 and 12. Air is supplied to the drum by the air inlet pipe 17 which discharges into a Venturi tube 18 having a fuel nozzle 19 discharging in its throat. The mixture of air and fuel entering at 14 travels circumferentially around the heated drum, the air being heated and the fuel

vaporized, the air after it is heated and the fuel after it is vaporized passing toward the center of the drum where it enters the distributor tube 20, being directed inward by the deflectors 21 formed in the wall of the tube. The heated and vaporized mixture then flows axially through the tube toward the burner sections 11 and 12. The upper section 11 is composed of a plurality of superimposed rings 22 spaced apart by thin washers 23 and covered by a cap 24, bolts 25

passing through the rings and washers securing the section to the vaporizing drum. The section 12 comprises two or more rings 26 and is closed by a cover 27, the rings and cover being spaced apart at their peripheries to provide spaces through which the mixture may flow. The vaporized fuel and air flows radially outward between the rings

composing the burner sections where it is ignited and burns with a short, intense, blue flame. Flame from the lower section 12 flows outward across the bottom of the vaporizing drum and then passes upward through the passages 28 and mixes above the drum with the hot gases from the section 11.

The burner sections 26, 27 are secured to the drum by bolts 29 which also serve to 10 secure the body portion 13 of the pilot burner to the vaporizing drum, the section 27 closing both the burner section 12 and the pilot burner, as clearly shown in Fig. 1. The body 13 of the pilot burner which 15 is hollow has a central outlet 30 and an inlet 31 near its periphery. The cap 27 which closes the pilot burner is spaced therefrom at its periphery to form a narrow opening 32 for the vaporized mixture. The 20 air inlet pipe 33 secured in the opening 31 is closed at its upper end near which it has a side aperture 34 within which the end of a fuel pipe 35 is disposed, as best shown in Figs. 3 and 9. The air and fuel pipes 25 33 and 35 discharge tangentially into the body of the pilot burner in the same manner that the main fuel and air pipes discharge tangentially into the main vaporizing drum and the vaporized fuel and air leave the 30 pilot vaporizing body through the central opening 30 flowing outward through the aperture or slot 32 where they are ignited, the heat therefrom keeping the drum 10 hot and through the flange 36 transmitting 35 the heat back to the body of the pilot burner to keep it at a vaporizing temperature. The air inlet pipe 33 is connected to the air pipe 33' which extends upward into the air inlet pipe 17 and is bent rearwardly to catch 40 air flowing through the pipe 17. A throttle valve 36' for controlling the main burner is disposed in the air inlet pipe 17 beyond its connection with the pipe 33'. When the throttle 36' is open, both the 45 main and pilot burners are in operation, but when the throttle is closed, the supply of air to the main burner only is shut off, the pilot light continuing to burn, keeping the main drum 10 sufficiently hot to vaporize the 50 fuel when the main burner is again turned on. A cover plate 37 secured to the lower end of the drum 10 has a central opening 38 through which flame from a torch or other burner may be applied to heat the pilot 55 light and drum 10 prior to first starting the main burner. An opening 39 is provided in the cover plate for purposes of inspection and through which a torch may be applied to ignite the pilot light in case 60 of an emergency or when first starting up.

Referring to Figs. 1, 2 and 7, an ignition tube 40 having a plurality of perforations 41 extends through the vaporizing drum and provides means for transmitting flame from the lower burner section 12 or

the pilot light to the upper section 11. Referring particularly to Fig. 2, it will be noted that the perforations 41 open on the side of the tube against which the whirling mixture in the drum impinges. This insures the tube 40 always being filled with combustible mixture so that flame may be propagated from the lower to the upper burner sections.

The lower section 26 is shown in detail 75 in Figs. 4 and 5 and has a plurality of lugs 42 on its upper surface and 43 on its lower surface spacing it from the other ring and from the cover plate 27 to provide apertures through which the combustible mixture may 80 flow. Similarly, the cover plate 27 has lugs 44 on its lower face to provide the slot 32.

In the operation of my burner, heat from 85 a torch or other apparatus is applied to the burner through the aperture 38 heating the drums of the pilot light and the main burner until their temperature is sufficient to vaporize the fuel. Air under low pressure is then supplied to the pipe 17, the 90 throttle valve 36' being open so that the air flowing into the main drum 10 picks up fuel from the nozzle 19 carrying it into the drum and around its heated periphery 95 where the air will be heated and the fuel vaporized, the heated air and fuel passing toward the center of the drum and eventually flowing out through the burner gratings 11 and 12. The mixture flowing out between the rings 26, 27 may then be ignited 100 by heat from a torch through the opening 38 or an igniter may be inserted through the opening 39. The flame from the lower section 12 spreads out over the bottom of the 105 drum and passes upward through the passages 28. This flame will ignite the mixture in the pipe 40 which will flash up and ignite the gases flowing out through the upper grating 11. When it is desired to 110 shut down the burner, the throttle 36' will be closed which shuts off the main burner but the pilot light continues to burn, air flowing through the inlet pipe 33', picking up fuel from the nozzle 35 and discharging 115 it tangentially into the drum 13 where it becomes vaporized and flows out through the central opening 30 and slot 32 and continues to burn. Flame from the pilot burner spreads out over the lower face of the 120 main drum and keeps it sufficiently hot so that the burner may again be started by opening the throttle valve. While the pilot light is burning, the flame therefrom impinges on the flange 36 and is transmitted back to the body 13 keeping it sufficiently 125 hot to vaporize the fuel.

While I have described one embodiment 130 of my invention in considerable detail, it is to be understood that I do not desire to be limited thereto but claim as my inven-

tion all modifications that may fall within the scope of my claims or embodying the general principles set forth therein.

What I claim as new and desire to secure 5 by Letters Patent is:

1. In a burner, the combination of a vaporizing drum having a tangential inlet and an axially discharging outlet, means for heating the drum, means for supplying a 10 mixture of fuel and air to the inlet whereby it is vaporized by heat from the drum, and a burner connected to the drum and receiving the vaporized mixture from the outlet.
2. In a burner, the combination of a circular vaporizing drum having a tangential inlet and a central outlet, means for supplying a mixture of fuel and air to the inlet, means for heating the drum, means for directing the vaporized mixture to the central 15 outlet, a burner secured to the drum over the outlet and receiving the vaporized mixture, and means for igniting the mixture at the burner.
3. In a burner, the combination of a circular vaporizing drum having an inlet in its periphery and an end outlet, means for heating the drum, means for supplying a mixture of fuel and air to the inlet whereby it will be vaporized by heat in the drum, and a burner co-axial with the end outlet and receiving vaporized mixture therefrom.
4. In a burner, the combination of a circular drum having a side inlet and an end outlet, an air inlet pipe connected to said inlet, a fuel nozzle discharging into said pipe, a main burner connected to the drum to receive vaporized mixture from said outlet, a secondary burner adapted to heat said drum, a secondary air inlet pipe connected to said first named air inlet pipe and discharging into said secondary burner, and a fuel nozzle for said second burner.
5. In a burner, the combination of a circular drum having a side inlet and an end outlet, an air inlet pipe connected to said inlet, a fuel nozzle discharging into said pipe, a main burner connected to the drum to receive vaporized mixture from said outlet, a secondary burner adapted to heat said drum, a secondary air inlet pipe connected to said first named air inlet pipe and discharging into said secondary burner, a fuel nozzle for said second burner, and a throttle valve in said first named air inlet pipe between the fuel nozzle and connection to the secondary air inlet pipe.
6. In a burner, the combination of a circular drum having a side inlet and an end outlet, an air inlet pipe connected to said inlet, a fuel nozzle discharging into said pipe, a main burner connected to the drum to receive vaporized mixture from said outlet, a secondary burner adapted to heat said drum, a secondary air inlet pipe connected to said first named air inlet pipe and discharging
- into said secondary burner, a fuel nozzle for said second burner, means for lighting said secondary burner, and a throttle valve in said first named air inlet pipe between the fuel nozzle and connection to the secondary air inlet pipe.
7. In a burner, the combination of a circular drum having a side inlet and an end outlet, an air inlet pipe connected to said inlet, a fuel nozzle discharging into said pipe, a main burner connected to the drum to receive vaporized mixture from said outlet, a secondary burner adapted to heat said drum, a secondary air inlet pipe connected to said first named air inlet pipe and discharging into said secondary burner, a fuel nozzle for said second burner, means for lighting said secondary burner, a throttle valve in said first named air inlet pipe between the fuel nozzle and connection to the secondary air inlet pipe, and means for lighting said main burner from said secondary burner.
8. In a burner, the combination of a circular vaporizing drum having a circumferential inlet and top and bottom outlets, means for supplying a mixture of fuel and air to the drum through the inlet, a burner connected to the top outlet, a burner connected to the lower outlet, means for igniting the lower burner, and means for igniting the upper burner from the lower burner.
9. In a burner, the combination of a circular vaporizing drum having a circumferential inlet and top and bottom outlets, means for supplying a mixture of fuel and air to the drum through the inlet, a burner connected to the top outlet, a burner connected to the lower outlet, means for igniting the lower burner, means for igniting the upper burner from the lower burner, and means for directing the products of combustion from the lower burner around the drum.
10. In a burner, the combination of a circular drum having a circumferential inlet and a central outlet on its bottom side, means for supplying a mixture of fuel and air to the inlet, a burner connected to said outlet, a secondary burner for heating said drum, means for igniting said secondary burner, and means for directing vaporized fuel and air from the drum to said first named burner.
11. In a burner, the combination of a circular drum having a tangential inlet and top and bottom outlets, top and bottom burners connected to the respective outlets, means for supplying a mixture of air and fuel to the tangential inlet whereby it will be vaporized by heat from the lower burner as it travels in a spiral path in the drum toward the outlets.
12. In a burner, the combination of a hollow drum having a central outlet, means for heating the drum, means for supplying a

- 4
- mixture of fuel and air thereto, and a grating formed from a plurality of spaced rings secured to the drum in communication with the central outlet.
- 5 13. In a burner, the combination of a hollow circular drum having a tangential inlet and a central outlet, means for supplying a mixture of fuel and air to the inlet, a plurality of superimposed spaced rings forming a burner grating secured at one end to the casing in communication with the outlet, a cap closing the other end of the grating, a second burner for heating the drum, and a firing tube for carrying flame from the 10 second burner to the grating to ignite vaporized mixture issuing therefrom.
14. In a burner, the combination of a hollow circular drum having a tangential inlet and a central outlet, means for supplying a mixture of fuel and air to the inlet, a plurality of superimposed spaced rings forming a burner grating secured at one end to the casing in communication with the outlet, a cap closing the other end of the 15 grating, a second burner for heating the drum, and a perforated firing tube extending through the drum and adapted to transmit flame from the second burner to the grating to ignite vaporized mixture issuing therefrom.
15. In a burner, the combination of a drum having a tangential inlet and centrally disposed top and bottom outlets, burners connected to the respective outlets, means 20 for directing the hot gases from the lower burner around the drum, an air inlet pipe connected to the tangential inlet, a fuel 25 pipe and pilot burner beneath the drum, a second air inlet pipe connecting the first named pipe and pilot burner, a fuel supply pipe therein, a throttle valve in the first air inlet between the fuel nozzle and second inlet pipe, means for igniting the pilot burner, and means for communicating flame to the 30 top burner.
16. In a burner, the combination of a hollow drum having a tangential inlet and central outlet, means for heating the drum, means for supplying fuel and air to the 35 tangential inlet, a distributor sleeve in said outlet in communication with said drum, and a burner carried by the drum and receiving vaporized mixture from said distributor sleeve.
17. In a burner, the combination of a hollow body having a central outlet, an air inlet pipe discharging tangentially into said body, a fuel pipe in said inlet pipe, and a burner section secured to the body in communication with said outlet and having a 40 radial discharge.
18. In a burner, the combination of a hollow body having a central outlet, an air inlet pipe discharging tangentially into said body, a fuel pipe in said inlet pipe, a burner plate secured to the body over said outlet and spaced therefrom at its periphery, and a flange on said body extending into the 45 path of the products of combustion issuing from said burner plate.
- 65 In testimony whereof I affix my signature.
